by ## UNITED STATES PATENT OFFICE

RUDOLF LACK, OF BASEL, SWITZERLAND

TURBINE IMPELLER

Application filed May 11, 1929, Serial No. 362,164, and in Germany May 19, 1928.

The present invention refers to a rotatable impeller or runner of a turbine or hydraulic machine. It is known to provide the vanes for the impeller with means which permit their adjustment by turning them on radial axles or journals arranged in the hub of the wheel (Kaplan-turbine) for the purpose of regulating, especially for enlarging or diminishing the passages between the vanes within said rotor. This arrangement has several inconveniences. First, the vanes need with regard to their adjustment by radial journals a very complicated mechanism for their adjustment. Further, this mechanism may be only used, when the number of vanes and the waterhead are small.

The object of the invention is to avoid these inconveniences and to provide an impeller with means for regulating the width of its passages without turning the vanes on radial axles and to provide means for adjusting the vanes in their axial and radial relations and with respect to the direction of their rotation.

This object is attained by improvements illustrated in the accompanying drawing, in which: Figure 1 is a sectional side elevation of an impeller embodying the present invention. Fig. 2 is a top view of the entire impeller. Fig. 3 is a detailed sectional view on line I—I, Fig. 1. Fig. 4 is a detailed sectional view of two series or groups of vanes. This figure shows a diagrammatic development of the runner and more particularly the relative peripheral positions of the vanes and, for instance, by dotted lines certain vanes displaced axially in the direction of arrows. Fig. 5 is a similar detailed sectional view of two groups of vanes. This figure shows more particularly the relative peripheral positions of vanes and, for instance, by dotted lines certain vanes displaced radially and axially in the direction of arrows indicated.

The impeller is provided with two groups of vanes. The vanes *a* of the one group may be arranged in front of the other vanes *b* in axial direction. Preferably, the vanes *b* are offset opposite the water-passages formed between the vanes *a*, which are fastened to

the hub *c* of the impeller. The hub *c* is fastened to the shaft *d* and cut diametral to form slots *e* for receiving studs *f* of a cross-head *g* which is connected with the vanes *b* by means of an annular piece *h* or the like. 55 The cross-head *g* is rotatably mounted on a rod *i* which passes through the hollow shaft of the impeller and is provided with two shoulders, one above and the other below the cross-head through which it passes. The 60 most accurate displacement of the vanes and cross-head can be effected by the manipulation of this rod.

It will be evident that by longitudinal adjustment of the rod *i*, the stud *f* will be 65 moved backward or forward in the inclined slots *e* so as to impart to the vane *b* an adjustment in an axial direction with respect to the vanes *a*, that is, toward or from said vanes *a*, and that in such adjustment of the 70 rod *i* and studs *f* the vanes *b* will be partially rotated about an axis concentric with the propeller shaft, by means of which the angular relationship of the vanes *b* with respect to the vanes *a* will be changed, for the purposes described. 75

With regard to sufficient quantity or full admission of water, the groups of vanes *a* and *b* are spaced axially from another for one vane-length. At other conditions, especially with regard to small water-quantity or admission, the vanes *a* and *b* are drawn close in order to obtain an arrangement, in which the vanes *b* may effect as complementary members or continuations of the upper vanes *a*. By this vane structure and displacement the area of passages between them may be more advantageously increased or decreased. 85

In Figs. 4 and 5 are the groups of vanes represented in diagrammatic development. The Figs. 4 and 5 show, for instance, the initial and terminal position of the vanes *b* corresponding respectively to the greatest or smallest passages between the latter. Arrows show the directions in which the vanes *b* may be displaced. The vanes *b* are drawn into their terminal position close towards the vanes *a* as indicated by dotted lines. But any other intermediate position may be given to the vanes *b*, until the best adjust- 95

ment is found, and the adjustment may be changed at any time to suit new requirements.

5 The number of revolutions of the impeller remains equal at each position of vanes and admission of water.

10 The means for displacing the vanes *b* may be also combined with the ordinary turbine governor or means by which the water flow before entering the impeller is regulated automatically during working or idle hours.

I claim:

15 1. A rotatable impeller for hydraulic turbines having concentric shafts each provided with a row of vanes, and means for relatively adjusting said shafts to effect axial displacement of one row of vanes with relation to the other row of vanes.

20 2. A rotatable impeller for hydraulic turbines having concentric shafts each provided with a row of vanes, and means for relatively adjusting said shafts to effect axial displacement of one row of vanes with relation to the other row of vanes and angular adjustment of one row of vanes with respect to the other row of vanes.

25 In testimony whereof I have affixed my signature.

RUDOLF LACK.
